(57) **CLAIM**

The ornamental design for an electrical cord head, as shown and described.

DESCRIPTION

FIG. 1 is a front, top, left side perspective view of a electrical cord head according to the invention;
FIG. 2 is a front elevational view according to the invention; and,
FIG. 3 is a back elevational view according to the invention; and,
FIG. 4 is a right elevational view according to the invention, the left side elevational view being a mirror image thereof;
FIG. 5 is a top plan view according to the invention; and,
FIG. 6 is a bottom plan view according to the invention; and,
FIG. 7 is a back, bottom, left perspective view of an electrical cord head, according to the invention.
The broken lines in the figure drawings is included to show unclaimed environment that form no part of the claimed design.
